UNITED STATES PATENT OFFICE

ELIAS THOMAS ROBERTS, OF GREENWOOD, MAINE, ASSIGNOR TO E. L. TEBBETS SPOOL CO., OF LOCKE MILLS, MAINE

FEEDING DEVICE FOR AUTOMATIC LATHES

Application filed April 10, 1924. Serial No. 705,678.

This invention relates to an improvement in wood lathes to provide an automatic reciprocation of the headstock and to provide an automatic feeding device adapted to successively advance and position in the lathe the stock to be turned.

The object of the present invention is to provide automatic devices by means of which a less skilled workman may be employed and the turning operations greatly expedited.

Further objects will more particularly appear in the course of the following detailed description.

The invention consists in the novel construction, arrangement and combinations of parts as hereinafter more particularly described and claimed.

Seven sheets of drawings accompany this specification as part thereof in which like reference characters indicate similar parts throughout.

Fig. 1 is a fragmentary front elevation of the headstock end of a lathe.

Fig. 2 is an end elevation of the headstock end of the lathe.

Fig. 3 is a fragmentary front elevation partially in section of the headstock of a lathe.

Figure 3A is a fragmentary detail of mechanism illustrated at the lower right hand end of Figure 3, but shows the several parts moved to a different operative position.

Fig. 4 is a front elevation of the improved feeding mechanism, showing in dotted lines the relative position of the same as applied to a lathe.

Fig. 5 is a side elevation showing the improved feeding device applied to a lathe.

Fig. 6 is a fragmentary plan view showing a part of the headstock control mechanism.

Fig. 7 is a transverse cross sectional view taken on the line 7-7 of Fig. 6.

Fig. 8 is a detail transverse cross sectional view through the feeding mechanism showing in more detail the construction of the stock gripping members.

Figure 9 is a plan of the entire machine showing the relation of the feeding means to the head stock.

50 In accordance with the present invention

the lathe is provided with an automatically reciprocating headstock which advances from the end of the lathe to engage the stock to be turned and, having engaged the same advances it during the turning operation. At 55 the completion of the turning operation and, after the finished turning has been cut off, the headstock is withdrawn to the end of the lathe, the stub of the stock automatically removed, and the operation repeated. 60

An automatic stock feeding mechanism is further provided to advance and position a new piece of stock on each reciprocation of the headstock.

The structure and operation of the lathe may be briefly described in connection with the accompanying drawings in which 1 indicates the reciprocating headstock generally, which is controlled by a cable 2 wound upon drum 4 to draw it backwardly toward the 70 end of the lathe and is further controlled by a chain 3 to draw it forwardly toward the center of the lathe to engage the stock preliminary to the turning operation. The drum 4 is operated through suitable gearing through a pulley 5 which is controlled by a clutch 6 operated by lever 7. The upper end of lever 7 is connected to a bar 8 extending longitudinally of the lathe and passing through a guide lug 10 secured to headstock 80 1, bar 8 being provided with stop nuts 11-11 on either side of the lug 10, which stop nuts form abutments for compression springs 9 similarly located and designed to cushion the contact of said lug 10 against the nuts 80 11-11. When lug 10 advances rod 8 to the right, clutch 6 throws pulley 5 out of operative engagement through its intermediate gearing with the drum 4 and permits the operation of chain 3 through mechanism later 85 described to advance the headstock. When lug 10 advances rod 8 to the left, clutch 6 throws pulley 5 into operative engagement through its gearing with drum 4 thus retracting the headstock to the end of the lathe. 90

The chain 3 is attached at one end to the end of the lathe body as at 3' and thence passes over the top of the lathe and thence downwardly and is secured to a weighted piston 12 operated in a cylinder 13 adapted 100

to regulate and cushion its downward fall. The weighted piston 12 is preferably formed with a cavity 16 adapted to receive liquid or other weighting material which may be supplied as through a passage 17 normally closed 5 by a stop screw 18. The cylinder 13 is provided adjacent its top with a plurality of orifices 14 permitting the rapid escape of air from the cylinder in the early stages of the piston's descent and is further provided adjacent its bottom with a valve 15 permitting the rapid ingress of air and only a gradual egress of air, thus further contributing to the cushioning effect of the device. 10

The headstock 1 is operatively connected 15 to chain 3 by means of a lug 20 carried in a suitable housing 21, said lug 20 being formed as the end of a rack member 22 operated by a pinion 23, to the shaft of which is connected a lever 24 which is in turn connected by a toggle 25 with a lever 26 mounted on the headstock and having its opposite leg connected by a suitable joint 27 with a rod 28 extending longitudinally through the spindle 29 of the headstock. The spindle 29 is provided for 25 this purpose with a longitudinal bore 28' which is enlarged as at 30 to accommodate a stop member 31 secured upon rod 28 between which stop member 31 and a closure 30 gland 33 provided for the rod 28 is arranged a compression spring 32 tending normally to advance rod 28 toward the work-engaging or interior end of the spindle 29. This interior end of the spindle 29 is provided with a work 35 engaging part 34 having a conical threaded orifice 35 into which the tapered end 36 of the stock 37 is adapted to be threaded preliminary to the turning operation. The rod 28 normally projects into this threaded conical orifice 35 and when thus extended inwardly has retracted lever 26 to operate rack 22 and throw same downwardly so that lug 20 is in engagement with an upwardly projecting lug 19 provided upon one of the links of 40 the chain 3.

A lever 39 is pivotally mounted as at 38 upon headstock 1 extending at one end into a downwardly projecting heel 40 and provided on its rear end with a roller 41. An upwardly projecting stanchion 42 upon the end of the lathe proper as a forwardly directed cam face 43 adapted to contact roller 41 upon the headstock 1 approaching the end of the lathe to throw heel 40 downwardly to 55 knock the stub of stock 37 from the work engaging member 34.

By reason of the toggle 25 between levers 24 and 26 lugs 20 is maintained in contact with lug 19 in two operative positions of lever 26. 60 That is to say when lever 26 has been moved in a counterclockwise direction by advancement of rod 28 through the spindle and into the work receiving orifice 35 with the toggle straight as illustrated in Fig. 1 or again when 65 rod 28 has been forced backwardly and the

links of the toggle 25 broken downwardly as illustrated in Figure 3A. In the latter or broken position of toggle 25 it will be apparent that rack 22 and hence lug 20 are normally thrown downwardly by the toggle spring 25" but are free to play within reasonable limits short of completely straightening the toggle. The operation of this structure may be described in connection with the cycle commencing with the retraction of the headstock 75 toward the end of the lathe after the cut-off of a completed turning, carrying the stub of a piece of stock 37 as illustrated in Fig. 3, except that the lug 20 would be in position contacting lug 19, the toggle 25 being broken 80 downwardly as in Figure 3A. With the mechanism in this position roller 41 contacts cam face 43 and the heel 40 of lever 39 knocks the stock stub from the stock engaging member 34, thus permitting rod 28 to be 85 advanced through the spindle 29 by means of spring 32 rocking lever 26 in a counterclockwise direction to straighten toggle 25 as illustrated in Figure 1 still maintaining lug 20 in engagement with lug 19. At the 90 same time lug 10 has compressed spring 9 against the lock nut 11 adjacent the end of the lathe throwing clutch 6 to disengage pulley 5 from drum 4 thus permitting the weight 12 operative through chain 3 to reverse the 95 motion of headstock 1 and carry same forwardly toward the center of the lathe. When the headstock spindle 29 comes in engagement with the next piece of stock 37, the tapered end 36 of the stock is screwed into 100 threaded orifice 35, thus forcing rod 28 backwardly through spindle 29, rocking lever 26 clockwise, which operating through the straightened link 25 raises rack 22 to relieve lug 20 from lug 19, permitting at this point 105 in the operation of the machine the continued advance of chain 3 independently of headstock 1, which latter part is at this point engaged by other mechanism not shown and further advanced during the turning operation 110 proper. The turning operation forces the stock 37 still further into the threaded orifice 35, thus forcing rod 28 still further backwardly until the toggle 25 is broken downwardly by means of the set screw 25' 115 mounted on the housing 21. Upon the breaking of toggle 25 the toggle spring 25" operates to throw rack 22 downwardly so that as the headstock 1 passes lug 19, which has previously reached the limit of its stroke, lug 20 120 rises over lug 19 and falls again by means of the spring pressure into locking engagement 125 preparatory to the next backward movement of the headstock during which movement by means of the said engagement with lug 19 chain 3 is retracted, thus again elevating weight 12 in cylinder 13 preparatory to a repeat operation. To properly time the return movement of headstock 1 at the completion of the cut-off operation a cam 45 is mounted 130

upon the counter shaft 44 of the lathe adjacent the tailstock end and under this cam is pivoted as at 46 upon the end 47 of the lathe body a lever 48 controlled as by spring 49. 5 The lever 48 projects outwardly and normally in the path of rod 8 as is illustrated in Fig. 6. On the inner end of the lever 48 is pivoted on a vertical axis as at 50 a second lever 51 having two angularly disposed arms 52 and 53, the former adapted to be contacted by cam 45 when thrown into proper relation therewith. The arm 52 is, however, normally held by spring 55 from under cam 45 (see Fig. 6) with 10 the arm 53 projecting, however, in the path 15 of a finger 54 carried by the headstock. As the turning operation nears its completion lug 10 on the headstock compresses spring 9 against the stop nut 11 carried by rod 8 tending to force rod 8 to the left and thus throw 20 clutch 6 to bring pulley 5 into operative engagement to rotate drum 4 and through cable 2 retract the headstock. Movement of the rod 8 is, however, prevented by lever 48 projecting in its path until finger 54 carried by 25 the headstock engages arm 53 of lever 51 and forces arm 52 of said lever under cam 45, which cam at the proper time rocks lever 51 and 48 as a single unit upon pivot 46, thus 30 swinging lever 48 out of the path of rod 8, permitting the rod to slide to the left, thus starting the previously described mechanism and retracting headstock 1.

In association with the lathe comprising generally the mechanism thus described I apply stock feeding mechanism which comprises broadly a plurality of endless chains 108, arranged in spaced relation upon sprockets 107 mounted upon shafts 105—106 carried by suitable end frame members 101 which are 35 adapted to be secured as by lugs 102 to the body of the lathe and which are connected by suitable lateral rods and may be further supported directly from the floor as by a stanchion 104. The chains 108 are provided 40 with outwardly projecting spaced lugs 110 which constitute backs against which pieces of stock 37 may contact. The upper stretches 45 of the chains 108, it will be observed, constitute a substantially horizontal moving table 50 upon which the pieces of stock may be readily arranged by any unskilled workman (see Fig. 5).

The sprockets 107 are fixedly secured to their shaft 106 upon which is mounted a cam 55 or wiper wheel 128 adapted to be operated by pawl 127, carried by lever 126 freely mounted upon the shaft 106. The end frame members 101 extend upwardly above shafts 105 and 106 to provide pivot bearings 111 for a 60 pair of spaced rods 112, one pair on each end of the device, which project downwardly and are connected by pivot joints with bridge members 113 intermediate their ends and bridge members 124 at their lower ends. On 65 one side of the device a bell crank 114 is piv-

otally connected by one arm to bridge member 113 intermediate rods 112, said bell crank being pivoted on frame 101 intermediate the upper pivot supports 111 and has its upper arm 114^a connected by rod 115 to a bell crank 116, the other arm of which is connected as by rod 117 to a lever 118 which is in turn secured to a shaft 119, extending transversely of the lathe body to the front of the machine where it supports a lever 120, carrying upon its outer end a roller 121 adapted to engage cam face 122 of a bracket 123 secured to headstock 1.

By reason of the structure thus described, it will be apparent that as the headstock 1 approaches the end of the lathe (see Fig. 4) cam 122 will contact roller 121 and through the levers, bell cranks and rods described will operate to swing rods 112 successively forward and backward with relation to the endless chains 108. The bridge member 124 is connected as by rod 125 with a lever 126, so that upon each backward swing of rods 112, chains 108 are advanced a fixed distance in a clockwise direction while upon the forward stroke of rods 112 pawl 127 rides over the cam or wiper wheel and the chains remain stationary.

Between the bridge members 124 connecting the pairs of rods 112, one at each end of the feeding device, is mounted a rod 129 upon which are arranged in spaced relation a plurality of stock gripping members 130, which, except for the one nearest the tailstock end of the lathe are slidable upon rod 129 but not rotatable thereon. The gripping member nearest the tailstock end of the lathe is neither slidable nor rotatable upon shaft 129. The gripping members 130 are separated upon shaft 129 by compression springs 137 by which arrangement various sizes of stock may be handled without any adjustment of the mechanism as is illustrated in Fig. 4, from which it will be apparent that with a short piece of stock in the grippers as there illustrated the headstock shown in dotted lines will advance contacting first the gripper member 130 nearest the headstock and compressing same against compression spring 137 until it substantially contacts the next adjacent gripper member and so on until the stock engaging member of the headstock engages the tapered end of the short piece of stock held between the most remote grippers.

Longer pieces of stock up to the maximum capacity of the machine are engaged by the appropriate number of grippers as is well illustrated in this figure. It will further be noted that the bars 112 with bridge members 124 and rod 129 constitute what may be conveniently termed a cradle support for the gripping members adapted to rock said members to and away from the moving table formed by the endless chain conveyors.

Each of the gripping members 130 is com-

posed of two complementary members 131 and 132, the latter slidably but non-rotatably mounted upon shaft 129 and the former freely rotatable upon shaft 129. Each of these members comprises semi-circular gripping parts with rearwardly extending lugs 138 and 139, which are connected as by a spring 140 tending constantly to close the semi-circular parts together. The lower 10 gripping member 132 is preferably made in two parts, the outer portion 134 of the semi-circular gripping member being pivoted as at 135 to the inner portion 133 and connected therewith as by spring 136. Rod 142 is supported between frame members 101 and under rods 112 in the path of the rearwardly projecting lugs 139 of the upper gripping members 131 so that on the rearward stroke of rods 112, lugs 139 will contact rod 142 and throw 15 the upper gripping members 131 upwardly and backwardly as illustrated in Fig. 8, when the same are under the guide members 109 provided intermediate the sprocket chains 108 to direct the downward gravitation of the 20 stock 37 when released from the chains. By reason of the structure thus described it will be apparent that on the backward stroke of rods 112 gripper jaws 131 are thrown up and back as the latter come under guides 109 while at the same time lever 126 advances 25 chains 108 to permit a piece of stock 37 to slide down the guides 109 on to the lower gripper members 132. As the headstock 1 reaches the end of the lathe and cam 122 operates upon roller 121 the rods 112 are swung 30 forwardly by the intermediate lever mechanism previously described and in their forward movement lugs 139 of the gripping members 131 are released from rod 142 and thrown by springs 140 downwardly into contact with the stock 37, carrying the same forwardly and into proper position over the lathe body to be contacted by the headstock upon its return stroke. The gripper members 35 are withdrawn from the stock by the rods 112 gravitating back into their vertical position timed by the following mechanism:

On the tailstock end of the feeding device is mounted a bell crank 114 similar in all respects to that of the headstock and previously described in connection with the operative mechanism and connected by its arm 114^a with a rod 145, which extends vertically and is connected at its lower end with a bell crank 50 latch member 146, the other arm of which is adapted to be engaged by a pivoted latch member 147, having a cam lug 148 lying in the path of a downwardly projecting lug 149 carried by chain 3. When the stock has been 55 screwed into the stock engaging member 35 of the headstock spindle sufficiently to disengage lug 20 from lug 19, as previously described, chain 3 continues its motion until 60 the lug 149 contacts latch 148 and lifts same 65 from the latch bell crank 146, thus permitting

the pivoted rods 112 to gravitate backwardly, carrying the gripping members into their rearmost position to receive the next piece of stock and at the same time leave the stock properly engaged between the headstock and the tailstock of the lathe and unencumbered 70 for the turning operation. By reason of the pivot and spring connected structure of the gripping members 132 that gripping member passes freely backwardly and under the stock 75 in the lathe.

Having thus described my invention, what I claim as new and desire to secure by Letters Patent, is:

1. In a lathe, the combination of a reciprocating headstock having a stock-engaging part, means for reciprocating the headstock, means to connect the headstock with the headstock reciprocating mechanism, and means operated by the stock when in engagement 80 with the stock engaging part of the headstock to control the connecting means between the headstock and the headstock reciprocating means.

2. In a lathe, the combination of a reciprocating headstock having a stock-engaging part, means for reciprocating the headstock including a power-driven pull device and a counter-weight, means operated by the headstock to connect or disconnect the power with 90 the pull device, means adapted to connect or disconnect the headstock with the counter-weight, and means operated by the positioning of the stock in the stock-engaging part of the headstock to control the connecting means between the headstock and the counter-weight.

3. In a power-driven lathe having a reciprocating headstock and means for applying power to reciprocate said headstock, a timing mechanism for controlling the reciprocation of the headstock including a clutch adapted to connect or disconnect power from the head reciprocator mechanism, a rod operating by a longitudinal movement to control the clutch, a sliding cushioned engagement between the headstock and the rod, a pivoted stop adapted to be swung into and out of alignment with the rod, and means operated by the power drive for the lathe to rock 105 the pivoted stop.

4. In a lathe having a reciprocating headstock provided with a stock-engaging part, power-operated means to reciprocate the headstock in one direction and a counter-weight to reciprocate the headstock in the other direction, means connecting the headstock with the counterweight including a catch, a spring-controlled member adapted to be actuated by the positioning of stock in 110 the stock-engaging part, and toggle means interposed between said catch and said stock-actuated member.

5. In a lathe having a reciprocating head with a stock-engaging part, a lever pivoted 115

on the head having a downturned heel adjacent the stock-engaging part, a cam face fixed with relation to the lathe adapted to engage the lever to rock same to knock the stock-stub from the stock-engaging part.

5 6. A feeding device for lathes and the like, comprising a movable table, a plurality of stock gripping members, a cradle support for said gripping members, means connecting the cradle support and the table whereby the rocking of the cradle toward the table advances the table towards the gripping members, and means for rocking the cradle.

10 7. A feeding device for lathes and the like, comprising a movable table, a plurality of stock gripping members, a cradle support for said gripping members, means connecting the cradle support and the table, whereby the rocking of the cradle toward the table advances the table towards the gripping members, means for opening the gripping members as they approach the table, means for closing the gripping members as they are 20 withdrawn from the table, and means for rocking the cradle.

25 8. A feeding device for lathes and the like, comprising a movable table, a stock gripping member, a cradle support for said gripping member, said cradle having a pivoted mount above the table, means for rocking the cradle away from the table, means for locking the cradle at its outermost position from the table, and means for releasing the cradle to 30 permit its gravitation back toward the table.

35 9. A feeding device for lathes and the like, comprising a movable table, a stock gripping member, a cradle support for said gripping member whereby the gripping member may be rocked to and away from the table, means connecting the cradle and the table whereby the rocking of the cradle will advance the table, means for locking the cradle in its farthest position from the table, means for periodically releasing the cradle from 40 said lock, and means for rocking the cradle.

45 10. In a feeding device for lathes and the like, a stock gripping member comprising supporting rod and two levers having complementary semi-circular leg members, one of said levers slidably but non-rotatably mounted on the supporting rod, the other lever both 50 slidably and rotatable with respect to the supporting rod.

55 11. In a feeding device for lathes and the like, a stock gripping member comprising a supporting rod and two levers having complementary semi-circular leg members, one of said levers slidably but non-rotatably mounted on the supporting rod and having its semi-circular leg jointed by a spring controlled hinge, the other lever being both slidably and rotatable with respect to the supporting rod.

60 65 12. In a feeding device for lathes and the

like, a stock gripping member comprising a supporting rod, and two levers having complementary leg parts, one of said levers slideable but non-rotatable on said rod and the other lever both slideable and rotatable with respect to the rod and spring means tending to draw complementary leg parts of said levers together.

70 13. In a feeding device for lathes and the like, a stock gripping member comprising a supporting rod, and two levers having complementary leg parts, resilient means adapted to draw said complementary parts together, means for movably supporting the supporting rod and means for tripping one of the 75 lever parts to separate the two complementary leg parts.

80 14. In a feeding device for lathes and the like, a stock gripping member comprising a supporting rod, a cradle support for said rod 85 whereby it can be rocked in a substantially horizontal plane, two levers having complementary leg parts, resilient means adapted to draw said complementary parts together, and a trip fixed in the path of one of said levers 90 whereby the complementary parts will be forced apart when the device passes a fixed point in its course.

95 15. In an automatic lathe having a reciprocating work engaging part, a movable table, a stock gripping device including resiliently closed pivoted jaws located between the edge of the table and the center of the lathe, means for periodically advancing the table and reciprocating the stock gripping device, a trip 100 adapted to open the pivoted jaws as the gripping device approaches the table, a latch adapted to hold the gripping device in its position central of the lathe, and means for releasing said latch controlled by the means 105 for imparting motion to the work engaging part of the lathe.

110 16. In combination, a lathe bed, a carriage movable along the bed for advancing a stick to be successively cut off, said carriage having a driven stick-rotating and advancing chuck, means for advancing the carriage and for automatically returning it after each complete advancement thereof, and means for automatically knocking a remnant of the stick laterally from the stick rotating chuck upon each return of said carriage.

In testimony whereof I affix my signature.
ELIAS THOMAS ROBERTS.
